2,236,322

METHOD AND COMPOSITION FOR IMPROVING MILLING PRODUCTS

Frederic H. Penn, Dallas, Tex.

No Drawing. Application January 23, 1940,
Serial No. 315,283

12 Claims. (Cl. 99—91)

My invention relates to the improvement of wheat flour and other milling products, including the baking and keeping qualities thereof, and more particularly has reference to a method and composition for the simultaneous bleaching and ageing or maturing of flour and the like.

According to present commercial practice, flour is bleached and aged in separate stages of treatment. The initial treatment is accomplished with gaseous nitrogen trichloride, which matures the flour. Nitrogen trichloride, in addition to being a maturing agent, also possesses bleaching properties, but, when used in sufficient amount to obtain a complete commercial bleach, injures the quality of the flour. Therefore, the amount of nitrogen trichloride used is insufficient to furnish a complete bleach and the necessary additional bleaching is obtained by a subsequent treatment with benzoyl peroxide, which has no maturing properties and which also injures the quality of the flour if used in sufficient amount to obtain a complete bleach. While the last-mentioned step is relatively simple, the gas treatment is quite cumbersome, requiring special contacting apparatus and corrosion-resistant equipment and accurate control over the gas, which presents many hazards and difficulties in use.

It is an object of this invention to bleach and age flour and the like in a single operation and to provide a finely divided or powdered composition, which, when intimately mixed with the flour, functions to effect a simultaneous bleaching and maturing of the milling product. The flour is thus improved in the two respects mentioned by the simple expedient of mixing the solid composition therewith and allowing sufficient time for the desired effects to take place.

A further object of my invention is to overcome the above-mentioned injurious effect of a bleaching quantity of benzoyl peroxide and the other active organic peroxides having flour bleaching properties. Benzoyl peroxide and the like, when used in sufficient amount to obtain a complete bleach, materially reduces the loaf volume factor or baking strength of the flour. According to my invention, there is used with a bleaching quantity of the peroxide a salt of a hexonic acid having flour maturing properties whereby to increase the loaf volume factor or baking strength of the flour and overcome the tendency of the bleaching quantity of peroxide to reduce these desirable qualities of the milling product. Additionally, I have found that the bleaching quantity of active organic peroxide

increases the maturing action of the hexonic acid salt over and above that obtained by the salt alone.

In my prior Patents Nos. 2,158,588 and 2,158,589, I have shown that simultaneous bleaching and ageing of flour and the like can be obtained by means of a powdered mixture of a bromate or iodate with an active organic peroxide, the latter seemingly functioning as an activator or accelerator for the solid bromates and iodates in their maturing of the dry milling product. According to the present invention, the bromates and iodates of my prior patents are replaced by alkali metal salts of hexonic acids derived from hexoses which similarly function with the active organic peroxides to bring about a simultaneous bleaching and ageing of flour and other milling products.

Accordingly, the solid bleaching and maturing composition of the present invention comprises a preformed mixture of an alkali metal salt of a hexonic acid and an active organic peroxide, that is, an organic peroxide which is sufficiently active in powdered form to effect at least a 90% flour bleach.

Potassium gluconate in powdered form is the preferred reagent for use with the active organic peroxide; sodium or potassium galactonate or mannionate are illustrative of other alkali metal salts of hexonic acids suitable for use in powdered form with the active organic peroxide.

As in my prior patents referred to, only certain organic peroxides are sufficiently active to cooperate with alkali metal salts of hexonic acids to effect the simultaneous bleaching and maturing, these being the aromatic and fatty acid peroxides which have sufficient activity in powdered form to accomplish at least a 90% bleach. Benzoyl peroxide is the preferred aromatic peroxide, while cinnamoyl peroxide and phenyl acetyl peroxide are other aromatic peroxides which I have found to be of sufficient activity and flour bleaching power for use with potassium gluconate and the like, in accordance with the invention. Suitable active fatty acid peroxides of sufficient bleaching power for my purpose are stearyl peroxide, lauryl peroxide and palmitic acid peroxide. These aromatic and fatty acid peroxides function with the finely divided or powdered alkali metal salts of hexonic acids to bring about a commercially satisfactory maturing and bleaching of dry flour. I believe that I am the first to discover that the active aromatic and fatty acid peroxides possess the property of

increasing the maturing action of potassium gluconate and the like upon dry milling products.

In practicing the method of this invention, the bleaching and maturing composition is fed directly into the flour at any convenient point during the milling operation, and intimately mixed therewith, by means of powder feeding machines now used in the mills, in the proportion of about one-half ounce to 196 pounds of flour. For thorough distribution of such small amounts of the composition in the flour, the composition should be in the form of a dry free-flowing finely divided powder. A satisfactory bleaching and ageing is obtained by exposure of the flour to the action of the composition for about twenty-four hours.

As illustrative of the preparation of a preferred composition, dry powdered commercial grade dicalcium phosphate or other suitable carrier is added to an equal weight of dry commercial grade granular benzoyl peroxide and the mixture ground to the desired fineness. With the powder thus obtained, there is now mixed dry powdered potassium gluconate in the proportion of nine parts potassium gluconate to ninety parts of the peroxide-phosphate mixture. The resultant mixture is then ready for use as a flour bleaching and ageing composition in the manner already described.

Since there are many grades of flour, the proportions of peroxide, potassium gluconate and carrier, as well as the amount of the composition required for effective bleaching and maturing, should be determined by tests in particular cases.

The proportions here stated are by weight.

The compositions of this invention improve the color and baking qualities of the flour. Loaf volume is one of the most important, if not the most important, indication for determining the value of the baking qualities of the flour. The volume of the baked loaf of bread is measured in cubic centimeters and denotes the exact size of the loaf produced. Small volume, as obtained with untreated or unmatured flour, indicates low baking strength, while large volume indicates high baking strength, which is apparently brought about by the maturing of the flour.

Illustrative of the advantages and effectiveness of my compositions, a fresh milled hard wheat bakers' flour was treated so that the tests corresponded to the use of one-half ounce of the composition to one barrel (196 lbs.) flour. The proportions of benzoyl peroxide and potassium gluconate, when used alone in the tests, corresponded to the amount used in the one-half ounce composition for treating one barrel (196 lbs.) of flour. The untreated flour yielded a loaf volume of 706 c. c. Benzoyl peroxide treated flour yielded a loaf volume of 685 c. c. Potassium gluconate treated flour yielded a loaf volume of 739 c. c., an increase of 33 c. c. more than is obtained with untreated flour. When treated with the benzoyl peroxide-potassium gluconate composition of this invention, the flour yielded a loaf volume of 765 c. c., an increase of 59 c. c. more than untreated flour and 26 c. c. more than is obtained with potassium gluconate treated flour.

According to the tests, benzoyl peroxide, when used alone and in sufficient quantity for a complete bleach of the flour, reduces the loaf volume. Potassium gluconate when used alone matures the flour somewhat but not to as great an extent as when mixed with the peroxide, and it does not have any bleaching effect. When benzoyl peroxide and potassium gluconate in combination are

incorporated into the dry flour during the milling process, a complete bleach and color removal is obtained, with an increase in loaf volume which is in excess of the volume obtained when either potassium gluconate or benzoyl peroxide is used alone.

In the appended claims I have characterized the peroxides as active and as having substantial flour bleaching properties in order to distinguish from those organic peroxides which are of insufficient activity and bleaching power to effect a commercial bleach. By "substantial flour bleaching properties" is meant the ability to bleach flour satisfactorily for commercial purposes, that is, to effect at least a 90% bleach. The term "alkinous metal" is used in the appended claims in its generic sense, that is, as inclusive of the alkali metals and alkaline earth metals.

Having described my invention, I claim:

1. A method for improving wheat flour and other milling products which comprises intimately mixing with the dry milling product a powdered alkinous metal salt of a hexonic acid and a powdered active organic peroxide having substantial flour bleaching properties, the peroxide being in sufficient amount to bleach the milling product and said salt being in sufficient amount to increase the loaf volume factor of the milling product, and subjecting the milling product in dry form to the simultaneous action of said salt and peroxide for a sufficient time to bleach and mature the product.

2. A method for improving wheat flour and other milling products which comprises intimately mixing with the dry milling product a powdered alkalinous metal salt of a hexonic acid and a powdered active aromatic peroxide having substantial flour bleaching properties, the peroxide being in sufficient amount to bleach the milling product and said salt being in sufficient amount to increase the loaf volume factor of the milling product, and subjecting the milling product in dry form to the simultaneous action of said salt and peroxide for a sufficient time to bleach and mature the product.

3. A method for improving wheat flour and other milling products which comprises intimately mixing powdered benzoyl peroxide and a powdered alkalinous metal salt of a hexonic acid with the dry milling product, the peroxide being in sufficient amount to bleach the milling product and said salt being in sufficient amount to increase the loaf volume factor of the milling product, and subjecting the latter in dry form to the simultaneous action of the peroxide and said salt for a sufficient time to bleach and mature the milling product.

4. A method for improving wheat flour and other milling products which comprises intimately mixing powdered benzoyl peroxide and potassium gluconate with the dry milling product, the peroxide being in sufficient amount to bleach the milling product and the gluconate being in sufficient amount to increase the loaf volume factor of the milling product, and subjecting the latter in dry form to the simultaneous action of the peroxide and potassium gluconate for a sufficient time to bleach and mature the milling product.

5. A method for improving wheat flour and other milling products which comprises intimately mixing powdered benzoyl peroxide and potassium galactonate with the dry milling product, the peroxide being in sufficient amount

- to bleach the milling product and said potassium galactonate being in such amount to increase the loaf volume factor of the milling product, and subjecting the latter in dry form to the simultaneous action of the peroxide and said potassium galactonate for a sufficient time to bleach and mature the milling product.
6. A method for improving wheat flour and other milling products which comprises intimately mixing powdered benzoyl peroxide and potassium mannonate with the dry milling product, the peroxide being in such amount to bleach the milling product and the mannonate being in sufficient amount to increase the loaf volume factor of the milling product, and subjecting the latter in dry form to the simultaneous action of the peroxide and potassium mannonate for a sufficient time to bleach and mature the milling product.
- 10 7. A flour bleaching and maturing composition comprising a dry free-flowing powdered mixture of an active organic peroxide having substantial flour bleaching properties, and a sufficient quantity of an alkalinous metal salt of a hexonic acid to overcome the loaf volume reducing factor of the peroxide.
- 15 8. A flour bleaching and maturing composition comprising a dry free-flowing powdered mixture of an active aromatic peroxide having substantial flour bleaching properties and a sufficient quantity of an alkalinous metal salt of a hexonic acid to overcome the loaf volume reducing factor of the peroxide.
- 20 9. A flour bleaching and maturing composition comprising a dry free-flowing powdered mixture of benzoyl peroxide and a sufficient quantity of an alkalinous metal salt of a hexonic acid to overcome the loaf volume reducing factor of the peroxide.
- 25 10. A flour bleaching and maturing composition comprising a dry free-flowing powdered mixture of benzoyl peroxide and a sufficient quantity of potassium gluconate to overcome the loaf volume reducing factor of benzoyl peroxide.
11. A flour bleaching and maturing composition comprising a dry free-flowing powdered mixture of benzoyl peroxide and a sufficient quantity of potassium galactonate to overcome the loaf volume reducing factor of the benzoyl peroxide.
12. A flour bleaching and maturing composition comprising a dry free-flowing powdered mixture of benzoyl peroxide and a sufficient quantity of potassium mannonate to overcome the loaf volume reducing factor of the benzoyl peroxide.

FREDERIC H. PENN.

CERTIFICATE OF CORRECTION.

Patent No. 2,236,322.

March 25, 1941.

FREDERIC H. PENN.

It is hereby certified that error appears in the printed specification of the above numbered patent requiring correction as follows: Page 2, second column, line 16, and line 24, claim 1, for "alkinous" read --alkalinous--; and that the said Letters Patent should be read with this correction therein that the same may conform to the record of the case in the Patent Office.

Signed and sealed this 5th day of August, A. D. 1941.
